UNITED STATES PATENT OFFICE.

LAWRENCE HARPER, OF SOUTH OLIVE, OHIO.

MILK BOTTLE.

Application filed February 11, 1927. Serial No. 167,448.

This invention relates more especially to means for promoting the preventing of contamination of milk.

Milk is peculiarly subject to contamination by dirt, and germs carried by dirt, and it is therefore of great importance in the interest of public health that every measure possible be taken to preclude access of germs or dirt thereto. As far as my observation extends 10 it is now customary to deliver milk to the consumer in bottles provided with a specially prepared paper cap sprung into a seat, recess or rabbet around the interior side of the mouth of the bottle; but because such a cap 15 when seated lies entirely below the plane of the upper rim of the mouth of the bottle there is formed around the junction of the cap with the mouth a corner into which dust and other forms of dirt collects, it being difficult, if 20 not impossible, to remove such dirt from such corner even though particular pains are taken to do so. When such a cap is employed more or less of the dirt is quite likely to break off and fall into the milk when the cap is 25 lifted out.

The object of the present invention therefore is to provide a construction whereby the upper surface of the cap coincides with or projects slightly above the inlet to the bottle; 30 and to adapt the invention to the vast number of bottles of the sort now in use so that they may be still utilized.

The invention is embodied in the example herein shown and described the features of 35 novelty being finally claimed.

In the accompanying drawing—

Figure 1 is a side view of an ordinary milk bottle with the neck and mouth in section showing my invention applied thereto.

Fig. 2 is a top plan view of a metallic crown or cap-receiving member spread out and before application to the mouth of the bottle.

Fig. 3 is a side view of the neck and lip of 45 the bottle showing the member shown in Fig. 2 applied thereto.

In the views 5 designates the bottle which is of the ordinary form with the usual rabbet 50 around the inner side of the mouth or lip thereof.

The crown member is preferably stamped or pressed in generally circular form out of a sheet of suitable metal with a central opening 7 having a downwardly extending lip 8 55 to enter and fill the usual rabbet around the

mouth of the bottle and an upwardly extending lip 9 annularly offset from the inner wall of said downwardly extending lip. Extending from the central ring-like portion of the member are petal-like portions 10 each having its sides cut so that when they are bent down around the exterior of the lip of the bottle from a position shown by broken lines Fig. 1 they close substantially together with their edges meeting as shown in Fig. 3 thereby forming a continuous armor substantially confining the lip at its exterior side. The petal-like portions 10 are bent inward at the outer ends to hug at the lower ends the wall of the lip near its base and said ends can be 60 beaded or thickened as shown at 11 so that when pressed home a slight space is left between the petal-like portions and the lip to permit a cushion effect when the crown piece is subjected to blows on the side due to rough 65 handling of the bottles. From the upper edge of the upwardly extending lip 9 of the central portion the crown slopes constantly downward and away from the inlet to the bottle. The character 12 designates the paper 70 cap which can be of the usual form. The vertical wall of the seat can be formed with a slight circumambient grooving as shown in Fig. 1 so as to bite into the rim of the paper cap to make a firm and more difficultly penetrable joint of the cap with the seat.

The crown piece can be applied to the bottle while hot, it shrinking into firm contact with the bottle upon cooling, and in some instances the crown may be first bent to the 80 required form and sprung into position on the bottle.

It will be observed therefore that dirt and dust accumulating on the cap tends to fall away from the cap and the crown when the 95 bottle is ordinarily handled. It is also obvious that the cap before removal can be wiped off completely with a clean rag there being no corners into which the dirt and dust is carried by the wiping operation.

It will be further observed that the crown piece becomes a permanent portion of the bottle and forms an armor to prevent breaking of the glass at the mouth of the bottle.

The forms of the parts can be changed 105 without departing from the gist of the invention as claimed.

What I claim is:

1. A milk bottle having a metallic armor 110 with a central opening, a cap seat around said

opening at its upper side and a paper cap seated therein having its upper portion flushing with the inlet to the bottle.

2. A milk bottle having a metallic armor with a central opening, a cap seat around said opening at its upper side and a paper cap seated therein having its upper portion flushing with the inlet to the bottle, the external surfaces of the bottle around and ad-

jacent to said cap seat sloping at all points 10 downward away from said seat.

3. An armor for the lip of a milk bottle containing a central opening with a cap seat therearound at its upper side and petal-like portions bent into edgewise coincidence with one another and to embrace and entirely enclose the exterior of the lip. 15
